ATTORNEY

UNITED STATES PATENT OFFICE.

WILLIAM C. PAUL, OF NEWARK, NEW JERSEY, ASSIGNOR TO REFLEX CO., OF NEWARK, NEW JERSEY, A CORPORATION OF NEW JERSEY.

LAMP.

1,211,750.

Specification of Letters Patent.

Patented Jan. 9, 1917.

Application filed March 16, 1916. Serial No. 84,563.

To all whom it may concern:

Be it known that I, WILLIAM C. PAUL, a citizen of the United States, residing in the city of Newark, in the county of Essex and State of New Jersey, have invented certain new and useful Improvements in Lamps, of which the following is a full, clear, and exact description, such as will enable others skilled in the art to which it pertains to make, construct, and use the same, reference being had to the accompanying drawings, and to numerals of reference marked thereon, forming a part of this specification.

My invention relates to improvements in lamps for automobiles and other vehicles.

The principal object of my invention is the production of a lamp which shall be simple in construction, comparatively inexpensive in cost, comprising a minimum number of parts, the lamp giving forth a powerful shaft of light, the top of which is level with the top of the opening in the front of the casing, and which from that elevation extends forward and downward to the road, spreading laterally to the desired degree, and being of a length that is entirely adequate for purposes of safety and convenience, said shaft of light having in it no upwardly directed rays capable of being cast into the eyes of persons approaching from the opposite direction.

With this end in view, my invention consists in certain novelties of construction and arrangements of parts, as hereinafter set forth and pointed out in the claims.

While the preferred forms of my invention are illustrated in the accompanying drawings, yet it is to be understood that minor detail changes may be made without departing from the scope thereof.

In the accompanying drawings, Figure 1 represents a front elevation of a lamp embodying my invention; and Fig. 2 represents a vertical central section taken on line $x-x$ of Fig. 1.

Similar numerals of reference refer to like parts throughout the specification and drawings.

In the drawings, the lamp casing is illustrated as consisting essentially of two parts, namely, the base 1 and the hood 2 secured thereto along the line 3, in any desired or convenient manner. Secured to the front of

the hood in any suitable manner is a bezel 4 of any desired or convenient shape. 55

The illuminating means of the lamp is located in the base 1 of the lamp, and comprises an incandescent globe 5, a filament 6 and the socket 7. The filament 6 may be connected to any suitable source of electricity, 60 such as for instance, the batteries usually carried by an automobile.

The construction of the base as clearly indicated in the drawings is in the form of a parabola, the interior surface of which 65 is preferably highly polished, and the axis of the parabolic base is inclined rearwardly from the perpendicular, in order that the rays cast by the incandescent lamp will be cast upon a preferably polished interior surface of the hood 2, and be projected by said surface of the hood 2 forward and downward, so as not to be cast into the eyes of persons facing the lamp. The hood 2 in its preferred form, consists essentially 75 of an elbow, with a flattened portion as indicated at 8, said flattened portion having a reflecting surface, preferably highly polished, in order to receive and reflect the rays cast by the light upon the parabolic surface 80 of the base 1.

As illustrated in Fig. 2 of the drawings, the hood 2 may consist of an unbroken curved surface, as indicated in dotted lines, in which case, the flattened portion 8 of the 85 hood 2 may be dispensed with, and the curved surface being polished and utilized to receive the reflected light from the parabolic base 1, and in turn be cast by said surface downward and outward upon the 90 roadway.

The present invention provides a very efficient and exceedingly simple lamp, the same being constructed of a minimum number of parts, and reduced to the simplest 95 operative efficiency, said parts being of such shape as to lend themselves readily to manufacture by the use of suitable punches and dies from ordinary sheet metal.

I am aware that changes may be made 100 in the several arrangements of the various parts, as well as in the details of construction thereof, without departing from the scope of my present invention; hence I do not wish to be limited to the arrangements 105 and combinations of parts as herein shown

and described, as obvious modifications will suggest themselves to those skilled in the art.

Having thus described my invention, what I desire to secure by Letters Patent is:—

- 5 1. A non-glaring lamp for vehicles comprising a casing having a light outlet opening, a reflector behind said opening inclined rearwardly and downwardly from adjacent the top of said opening to substantially the bottom of the opening, and a concave reflector mounted below said opening and adapted to project light upwardly and rearwardly upon the inclined reflector.
- 10 2. A non-glaring lamp for vehicles comprising a reflector casing having a light outlet opening, said reflector casing being formed with a substantially flat reflecting surface extending from adjacent the top of the opening rearwardly and downwardly,
- 15 20 said reflector casing adjacent the bottom of the opening being formed into a concave reflector adapted to project light upwardly upon the inclined reflector.
- 25 3. A non-glaring lamp for vehicles having a circular perpendicular opening, a reflector behind said opening inclined rear-

wardly and extending from the top to substantially the bottom of said opening, and a paraboloidal reflector mounted wholly below said opening and adapted to project 30 light rearwardly and upwardly upon the inclined reflector.

4. A non-glaring lamp for vehicles comprising a reflector casing having a circular light-emitting aperture, said reflector casing behind said aperture being inclined from a point adjacent and on one side of said aperture rearwardly across the axial line of said aperture and formed into a substantially flat reflecting surface, said reflector casing being formed on the opposite side of said aperture into a paraboloidal reflector mounted wholly on one side of the aperture and with its axis inclined rearwardly from the perpendicular to the axial 40 line of said aperture.

This specification signed and witnessed this 14th day of March, 1916.

WILLIAM C. PAUL.
